(57) CLAIM

The ornamental design for a sideboard, as shown and described.

DESCRIPTION

FIG. 1 is a perspective view of a first embodiment of a sideboard showing our new design;

FIG. 2 is a top plan view thereof;

FIG. 3 is a front elevation view thereof;

FIG. 4 is a right side elevation view thereof, the left side being a mirror image;

FIG. 5 is an enlarged fragment of a portion of the sideboard shown in FIG. 1 and labeled 5;

FIG. 6 is an enlarged fragment of a portion of the sideboard shown in FIG. 1 and labeled 6;

FIG. 7 is an enlarged fragment of a portion of the sideboard shown in FIG. 1 and labeled 7;

FIG. 8 is a perspective view of a second embodiment of a sideboard showing our new design;

FIG. 9 is a top plan view thereof;

FIG. 10 is a front elevation view thereof;

FIG. 11 is a right side elevation view thereof, the left side being a mirror image;

FIG. 12 is an enlarged fragment of a portion of the sideboard shown in FIG. 8 and labeled 12;

FIG. 13 is an enlarged fragment of a portion of the sideboard shown in FIG. 8 and labeled 13; and,

FIG. 14 is an enlarged fragment of a portion of the sideboard shown in FIG. 8 and labeled 14.

The broken lines show environmental subject matter and form no part of the claimed design. The fragmentary showing of wood grain in FIGS. 1-4 and 8-11 and shown in detail in FIGS. 5-7 and 12-14 is understood to be repeated throughout the surfaces shown. The second embodiment is shown with a symbolic break in length in FIGS. 8-10 and those portions of the article between the break lines form no part of the claimed design.
